UNITED STATES PATENT OFFICE.

HARRY R. HOLDEMAN, OF INGLEWOOD, CALIFORNIA, ASSIGNOR TO ALLIED METAL INDUSTRIES, INC., A CORPORATION OF CALIFORNIA.

DESIGN FOR A SPANISH-EFFECT LIGHTING-FIXTURE PANEL.

Application filed August 23, 1926. Serial No. 18,816. Term of patent 3½ years.

To all whom it may concern:

Be it known that I, HARRY R. HOLDEMAN, a citizen of the United States, residing at Inglewood, in the county of Los Angeles and State of California, have invented a new, original, and ornamental Design for Spanish-Effect Lighting-Fixture Panel, of which the following is a specification, reference being had to the accompanying drawing, forming part thereof.

In the drawing, the figure is an elevational view of a representation of the design, a portion of the surface finish being shown, it being understood that the balance thereof, within the marginal border involves a mere repetition of such part more fully illustrated.

I claim:

The ornamental design for a Spanish-effect lighting fixture panel, as shown.

HARRY R. HOLDEMAN.
